WILLIAM B. HOLLINGSHEAD, OF TUCKAHOE, NEW YORK

ACOUSTIC DIAPHRAGM AND SIMILAR APPLIANCE

Application filed March 13, 1929. Serial No. 346,560.

My invention relates to acoustic diaphragms and analogous devices, and especially to means for damping, modulating, or otherwise controlling the vibrations of such devices.

In the term "acoustic diaphragms" I intend to include the vibratory diaphragms of phonograph recorders and reproducers, as well as the cones, diaphragms, or analogous vibratory elements of radio receivers and sound amplifiers.

The present application is a division and continuation in part of my prior application Serial No. 320,786 filed August 30, 1919, 15 with added modifications and improvements.

By study and experiment I have found that acoustic diaphragms and the like when permitted to vibrate freely or without restraint except by their normal support, as in a frame or casing, in many cases fail to provide a true or faithful reproduction of the original sound.

The principal object of the present invention therefore is to provide means for properly controlling, damping or modulating such diaphragms, etc., to reduce or eliminate false or excessive vibrations, and secure faithful recording or reproduction with preservation of overtones, and improved tone qualities.

A further object is to provide adjustable damping means in order to control damping or modulating effects and also to provide for unavoidable variations in the characteristics of the individual diaphragms or similar devices. These devices, even if supposedly identical, differ from each other, and adjustment of the modulating means is therefore in many cases necessary in order to secure the desired tonal results from the individual vibrating elements.

The characteristics and advantages of the invention are further sufficiently explained in connection with the following detail de-

scription of the accompanying drawings, which shows representative embodiments. After considering these examples, skilled persons will understand that many variations may be made without departing from the principles disclosed, and I contemplate the employment of any structures that are properly within the scope of the appended claims.

In the drawings:

Fig. 1 is a front elevation of a diaphragm and its case or housing, the arrangement selected being one adapted for phonographic recording or reproduction.

Fig. 2 is a section at 2—2, Fig. 1.

Fig. 3 is a front elevation of a modified structure.

Fig. 4 is a partial section, enlarged, at 4—4, Fig. 3.

Fig. 5 is a diagram, giving one illustration or theoretical operation of the invention devices.

Figs. 1 and 2 show one preferred embodiment of the invention, this being one of those disclosed in the above identified application. The diaphragm support or sound-box 1 as well as the diaphragm 2, may vary greatly in form, structure and arrangement, the particular structure shown being only representative, in the broader aspect of the invention. This particular device is intended for phonographic recording or reproducing, and for that purpose the case is connected to a neck portion 7, by which it is attached to any sound-vibration-transmitting arm (not shown); or the case 1 may be attached to the "tone arm" of a phonograph reproducer, in any known or suitable way. The case may be open or may have a closed back, as at 3.

The diaphragm may be of the "free" type, or may be supported in any suitable way, as by rings or gaskets 4 of suitable material, in some cases rubber or rubber composition, with or without clearance. The gaskets and diaphragm may be secured by an annular collar or outer ring 5, secured by screws 6, 70

and the screws may if desired be arranged to control the compression of the diaphragm-supporting rings or gaskets. A stylus bar is connected to the diaphragm at a suitable point and has means for supporting the stylus in any known or suitable way. The stylus connection may be at the center of the diaphragm as at 7^a in Figs. 1 and 2, or near one edge thereof, as at 7^b in Fig. 3, since I have found that in some cases more faithful response of the diaphragm to the original impulse is provided by the latter location.

As one suitable modulating means, I show certain parts or sectors of the diaphragm as engaged by damping points or plugs 9 and 10 respectively, (Figs. 1 and 2). These spaced plugs are shown as carried by a slide 11, circumferentially adjustable within a slot or annular guideway 12 provided in the outer ring member 5, above referred to. By means of this construction the damper may be adjusted circumferentially about a peripheral portion of the diaphragm to bring the damping elements into engagement with any two sectors or portions desired; and the slide can be easily adjusted until the best effect is obtained. This damping effect is indicated graphically in Fig. 5, where alternate portions 12 and 13 are designated as the crests of waves 14 and 15, from which it will appear that the dampers 9 and 10 check the vibrations of these portions or sectors of the diaphragm, while leaving the outer portions free to vibrate. The sinusoidal line 16 of Fig. 5 may otherwise be considered or explained as in effect a "string" of a musical instrument, representing a circle in the diaphragm at the same radius from the centre as the dampers 9 and 10. Evidently the dampers then establish nodal points in the same way that a node is produced in a string by fingering (as in a violin or similar instrument), thus practically "tuning" the diaphragm. Evidently by properly positioning and adjusting the dampers, one nodal point may be made to either favor or suppress excessive high notes (high frequency vibrations), while the other may similarly be made properly to control the low notes (low frequency vibrations).

Figs. 3 and 4 show a modification in which one of the dampers is adjustable in relation to the diaphragm. Each of the dampers 9^a and 10^a is carried by a short arm 20, and these arms have flanged peripheral or base portions 21 engaging in a channel formed by a flat ring 22 and an outer ring 23, secured to the case 1 in any suitable way, as by screws 6 of the previous example. Ring 23 is so formed and provided with a shoulder 24 as to slidably retain the damper-supporting arms and prevent their displacement from the guide channel. A similar arrangement may be provided in Figs. 1 and 2 to retain the slidable member 11 in its channel.

Either or both of the dampers (Figs. 3 and 4) may be moved in a circular direction to obtain the desired vibration controlling effect, one such adjusted position of one of the dampers being indicated in dotted lines at 28, Fig. 3; or if desired, one of the dampers may be fixed in position, as by a pin inserted at 25 through plate 23 and the base of the supporting arm 20.

Skilled persons will understand how the structural and operative principles disclosed may be applied to other acoustic diaphragms or sound reproducers, such as radio loud-speakers, or the sound reproducers of public address amplifying systems, etc.

I claim:

1. In combination with an acoustic diaphragm or analogous device, a plurality of dampers in contact with the diaphragm, and means for supporting at least one of the dampers adjustably in relation to the diaphragm to produce a variable nodal point thereon.

2. In combination with an acoustic diaphragm or analogous device, a plurality of dampers in contact with the diaphragm, and means for supporting the dampers adjustably in relation to the diaphragm to produce variable nodal points thereon.

3. In combination with an acoustic diaphragm or analogous device, a plurality of dampers in contact with the diaphragm, and means for supporting the dampers adjustably in relation to each other to produce a plurality of variable nodal points on the diaphragm.

4. In combination with an acoustic diaphragm or analogous device, a plurality of dampers in contact with the diaphragm, and means for supporting the dampers adjustably in relation to each other and to the diaphragm to produce a plurality of regulable nodal points therein.

5. In a structure of the character described, a diaphragm or analogous vibratory acoustic device, a support therefor, and a damper carried by the support and adjustable in a generally circumferential direction in relation to the diaphragm to produce a variable nodal point thereon.

6. In a structure of the character described, a diaphragm or analogous vibratory acoustic device, a support therefor, and a plurality of dampers mounted on the support and adjustable in a generally circumferential direction in relation to the diaphragm to produce a corresponding plurality of variable nodal points thereon.

7. In an appliance of the class described, the combination of a diaphragm, a support therefor including an annular channel, a damper-supporting element mounted for adjustable movement in the channel, and a damper carried thereby and opposed to the diaphragm to produce a variable nodal point thereon.

8. In an appliance of the class described, the

combination of a diaphragm, a support therefor including an annular channel, a plurality of damper-supporting elements mounted in the channel and at least one of them adjustable in a generally circumferential direction, and dampers carried by said elements and opposed to the diaphragm to produce in effect different nodal points therein.

5 10 In testimony whereof I affix my signature.
